(57) **CLAIM**

The ornamental design for an adhesive wrap for skate blade holders, as shown and described.

DESCRIPTION

FIG. 1 is a top view of an adhesive wrap for skate blade holders showing my new design;
 FIG. 2 is a bottom view thereof;
 FIG. 3 is a right side view thereof;
 FIG. 4 is a left side view thereof;
 FIG. 5 is a rear view thereof; and,
 FIG. 6 is a front view thereof.

1 Claim, 6 Drawing Sheets
